UNITED STATES PATENT OFFICE.

EDWARD H. BRUNNER, OF MEMPHIS, TENNESSEE.

KRAUT-PACK.

1,044,341.

Specification of Letters Patent.

Patented Nov. 12, 1912.

Application filed September 14, 1910. Serial No. 582,028.

To all whom it may concern:

Be it known that I, EDWARD H. BRUNNER, a citizen of the United States, residing at Memphis, in the county of Shelby and State 5 of Tennessee, have invented new and useful Improvements in Kraut-Packs, of which the following is a specification.

This invention relates to devices for packing kraut, pickles or the like in barrels, and 10 the object of the invention is to provide a simple and efficient device constructed in sections hinged together whereby it may be readily removed from the barrel or held in any adjusted position therein and whereby 15 certain portions of the barrel may be opened up for removal of the material therein without disturbing the remainder of the closure.

Further objects of the invention will appear as the following specific description is 20 read in connection with the accompanying drawing which forms a part of this application, and in which:

Figure 1 a top plan view. Fig. 2 is a section through the device showing the same 25 applied to a barrel. Fig. 3 is a plan view of a modified form. Fig. 4 is a detail sectional view of one of the hinged arms and staples.

Referring more particularly to the drawing 30 1 represents a square plate which is provided with a handle 2 for manipulating the device and which has secured on all four sides thereof hinge staples 3 to which the hinge arms 4 are connected. These hinge 35 arms are entered into staples on adjacent sides of the leaves 5 which are arranged on each side of the plate 1 and have their outer edges curved so that when lying in the plane, their combined peripheries form a complete 40 circle. Each of the leaves is movable independently upon the plate 1 and each is provided with a pair of aligned staples or 45 guide members 6 in which is slidably mounted the pointed barrel engaging tongues 50 which are adapted to enter the inside of the barrel and hold the leaves in adjusted position. Suitable operating handles 8 are bent up from the tongues so that the same may be conveniently manipulated.

50 In the modification shown in Fig. 3 the leaf holding plate is shown at 9 and has

hinged on opposite sides thereof the semi-circular leaves 10, which are shown to be provided with the barrel-engaging tongues, as described. In both instances the staples 55 on the leaves engage the hinge arms 4 loosely and carry the set screws 11 which engage the arms and hold the leaves in adjusted position. The ends of the hinge arm are provided with hooks 12 which provide 60 their disengagement with the staples.

Having thus described the invention, what I claim as new is:—

1. A kraut pack or the like comprising an attaching plate, a plurality of leaves, staple members secured to the leaves, U-shaped members hinged to the attaching plate and 65 slidably mounted in the staple members, for adjustably connecting the attaching plates to the leaves, and means for holding the U- 70 shaped members in adjusted position.

2. A kraut pack or the like comprising an attaching plate, a plurality of leaves, staple members secured to the leaves, U-shaped members hinged to the attaching plate and 75 slidably mounted in the staple members, for adjustably connecting the attaching plate to the leaves, and set screws for holding the U-shaped members in adjusted position.

3. A kraut pack or the like comprising an 80 attaching plate, a plurality of leaves, staple members secured to the leaves, U-shaped members hinged to the attaching plate and 85 slidably mounted in the staple members, for adjustably connecting the attaching plates to the leaves, and means for holding the U-shaped members in adjusted position.

4. A kraut pack or the like comprising an attaching plate, a plurality of leaves, staple members secured to the leaves, U-shaped 90 members hinged to the attaching plate and 95 slidably mounted in the staple members, for adjustably connecting the attaching plate to the leaves, and set screws for holding the U-shaped members in adjusted position.

In testimony whereof I affix my signature in presence of two witnesses.

EDWARD H. BRUNNER.
